(57) **ABSTRACT**

When printing is performed on a recording medium of a second size larger than a first size, a control portion, after passage of the recording medium of the first size at a position opposite a recording head before arrival of the recording medium of the second size at the position opposite the recording head, makes the recording head perform preparatory flushing processing in which ink is ejected toward openings from first nozzles that have not been set as target nozzles during printing on the recording medium of the first size but will be newly set as the target nozzles during printing on the recording medium of the second size.

INK-JET RECORDING APPARATUS

INCORPORATION BY REFERENCE

This application is based upon and claims the benefit of priority from the corresponding Japanese Patent Application No. 2021-117838 filed on Jul. 16, 2021, the entire contents of which are hereby incorporated by reference.

BACKGROUND

The present disclosure relates to an inkjet recording apparatus.

Conventionally, there are known inkjet recording apparatuses including a recording head. Conventional ink-jet recording apparatuses convey a recording medium using a conveying belt and eject ink from the recording head toward the recording medium being conveyed by the conveying belt to form an image on the recording medium.

SUMMARY

According to one aspect of the present disclosure, an ink jet recording apparatus includes a conveying belt, a recording head, and a control portion. The conveying belt is supported so as to be able to move around and conveys a recording medium by circulating. The recording head is arranged opposite the recording medium and has a plurality of nozzles that are arrayed in the width direction perpendicular to the circulation direction of the conveying belt. The recording head prints on the recording medium by ejecting ink from the nozzles. The control portion controls flushing processing by the recording head. The conveying belt has a plurality of flushing areas with openings formed in them. The flushing areas are arranged at predetermined intervals from each other in the circulation direction. The control portion sets the nozzles that face the recording medium during printing on the recording medium as target nozzles and, when a flushing area that does not overlap the recording medium faces the recording head, makes the recording head eject ink, as flushing processing, from the target nozzles toward the openings. When, after printing on the recording medium of which the size in the width direction is a first size, printing is performed on the recording medium of a second size that is larger, in the width direction, than the first size, the control portion, after passage of the recording medium of the first size at a position opposite the recording head before arrival of the recording medium of the second size at the position opposite the recording head, makes the recording head perform preparatory flushing processing in which ink is ejected toward the openings from first nozzles that have not been set as the target nozzles during printing on the recording medium of the first size but will be newly set as the target nozzles during printing on the recording medium of the second size.

BRIEF DESCRIPTION OF THE DRAWINGS

FIG. 1 is a schematic diagram of an ink-jet recording apparatus according to one embodiment;

FIG. 2 is a plan view of a recording portion in the ink-jet recording apparatus according to the one embodiment;

FIG. 3 is a block diagram of the ink-jet recording apparatus according to the one embodiment;

FIG. 4 is a schematic diagram of and around a conveying belt in the ink-jet recording apparatus according to the one embodiment;

2

FIG. 5 is a plan view of the conveying belt in the ink-jet recording apparatus according to the one embodiment;

FIG. 6 is a diagram showing the positional relationship between a flushing area of the conveying belt and recording heads in the inkjet recording apparatus according to the one embodiment;

FIG. 7 is a diagram showing the positional relationship between the flushing areas of the conveying belt and sheets in the ink-jet recording apparatus according to the one embodiment;

FIG. 8 is a diagram showing a state where sheets are being conveyed by the conveying belt in the ink-jet recording apparatus according to the one embodiment;

FIG. 9 is a diagram showing target nozzles in the ink-jet recording apparatus according to the one embodiment;

FIG. 10 is a diagram illustrating control of flushing processing and preparatory flushing processing performed in the ink-jet recording apparatus according to the one embodiment;

FIG. 11 is a diagram showing first nozzles and second nozzles in the ink-jet recording apparatus according to the one embodiment.

DETAILED DESCRIPTION

As an example of an inkjet recording apparatus according to an embodiment, a printer will be taken in the following description. For example, a printer prints an image on a sheet as a recording medium. Any of Various types of sheets such as an OHP sheet can be used as a recording medium.

<The Overall Structure of a Printer>

As shown in FIG. 1, a printer 100 according to an embodiment includes a first conveying portion 1 and a second conveying portion 2. The first conveying portion 1 feeds out a sheet S set in a sheet feeding cassette CA to convey it to a printing position. In a print job by the printer 100, printing is performed on the sheet S passing across the printing position. The second conveying portion 2 conveys the printed sheet S and discharges it onto a discharge tray ET.

Although not illustrated, for example, a plurality of sheet feeding cassettes CA are mounted in the printer 100. The sheets S set in the plurality of sheet feeding cassettes CA may be in the same size or in different sizes, in a print job by the printer 100, of the plurality of sheet feeding cassettes CA, the one in which the sheet S to be used in the print job is set as a sheet supply source, and the sheet S is fed from the sheet feeding cassette CA that is set as the sheet supply source.

The first conveying portion 1 includes a plurality of conveying roller members including a pair of registration rollers 11. The plurality of conveying roller members rotate to convey the sheet S. The pair of registration rollers 11 is configured as a pair of rollers that are kept in pressed contact with each other. A registration nip is formed between the pair of rollers. The sheet S fed from the sheet feeding cassette CA passes through the registration nip. The pair of registration rollers 11 rotates to convey the sheet S that passes through the registration nip toward a belt conveying portion 3, which will be described later.

The pair of registration rollers 11 is not rotating when the front end of the sheet S reaches the registration nip. At this point, the conveying roller members on the upstream side of the pair of registration rollers 11 in the sheet conveying direction are rotating. This helps correct a skew of the sheet S.

The printer 100 includes the belt conveying portion 3. The belt conveying portion 3 receives the sheet S from the first conveying portion 1 and conveys it. The belt conveying portion 3 includes a conveying belt 30. The conveying belt 30 is endless and is supported so as to be able to move around. The belt conveying portion 3 includes a plurality of stretching rollers 301. The plurality of stretching rollers 301 are rotatably supported. The conveying belt 30 is stretched around the plurality of stretching rollers 301 and moves around.

One of the plurality of stretching rollers 301 is coupled to a belt motor (not shown) and rotates by receiving a driving force from the belt motor. When the stretching roller 301 coupled to the belt motor rotates, the conveying belt 30 moves around and the other stretching rollers 301 rotate by following it.

The belt conveying portion 3 includes a suction unit 300. The suction unit 300 is arranged at the inner side of the conveying belt 30. In the conveying belt 30, a plurality of suction holes (not shown) that penetrate it in its thickness direction are formed.

The sheet S conveyed from the first conveying portion 1 reaches the outer circumferential face of the conveying belt 30. The suction unit 300 sucks the sheet S through the suction holes. The sheet S on the outer circumferential face of the conveying belt 30 is held by suction on the outer circumferential face of the conveying belt 30. The conveying belt 30 moves around with the sheet S held by suction on its outer circumferential face. The sheet S is thus conveyed.

In this way, the belt conveying portion 3 conveys the sheet S in the circulation direction of the conveying belt 30. That is, the circulation direction of the conveying belt 30 coincides with the conveying direction of the sheet S (the direction in which the sheet S advances).

The printer 100 includes a recording portion 4. The recording portion 4 is arranged opposite the outer circumferential face of the conveying belt 30. When the sheet S is held by suction on the outer circumferential face of the conveying belt 30, the sheet S and the recording portion 4 face each other across a gap left between them.

As shown in FIG. 2, the recording portion 4 includes four line heads 41 corresponding to different colors, namely cyan, magenta, yellow, and black. In FIG. 2, the line heads 41 for cyan, magenta, yellow, and black are identified by the suffixes "C", "M", "Y", and "K" respectively.

The line heads 41 for the different colors each include a plurality of (for example, three) recording heads 40. For example, the plurality of recording heads 40 for each color are arranged in a staggered formation in the direction perpendicular to the circulation direction of the conveying belt 30 (the conveying direction of the sheet S). In the following description, the direction perpendicular to the circulation direction of the conveying belt 30 is referred to simply as the "width direction".

The recording heads 40 are arranged opposite the outer circumferential face of the conveying belt 30 in the up-down direction across a gap left between them. In other words, the recording heads 40 are arranged at such a position as to face, in the up-down direction, the sheet S being conveyed by the conveying belt 30. Here, the up-down direction is the direction perpendicular to the circulation direction of the conveying belt 30 and also to the width direction.

The recording heads 40 each have a nozzle face that faces the conveying belt 30 (the sheet S on the conveying belt 30). The nozzle faces of the recording heads 40 have a plurality of nozzles 4N. The plurality of nozzles 4N in the recording

heads 40 eject ink of different colors corresponding to the recording heads 40. For example, the recording heads 40 all have the same number of nozzles 4N. The plurality of nozzles 4N in the recording heads 40 are arranged along the width direction of the conveying belt 30. In FIG. 2, the nozzles 4N are indicated by broken lines. In reality, the recording heads 40 have a larger number of nozzles 4N.

The recording portion 4 (recording heads 40), based on image data to be printed in a print job, ejects ink from the nozzles 4N toward the sheet S. The ink ejected from the recording portion 4 attaches to the sheet S. An image is thus printed to the sheet S. That is, the position between the conveying belt 30 and the recording heads 40 is the printing position. In other words, the position that faces the nozzle faces (nozzles 4N) of the recording heads 40 in the up-down direction is the printing position.

Here, out of the plurality of nozzles 4N, in the nozzles 4N which eject ink less often, the viscosity of ink increases over time. This results in nozzle clogging and degraded image quality. To suppress such inconveniences, the recording heads 40 perform flushing processing. In flushing processing by the recording heads 40, ink stagnant in the nozzles 4N is discharged. Nozzle clogging is thus suppressed. This will be described in detail later.

Back in FIG. 1, the printer 100 includes a drying unit 51 and a decurler 52. The drying unit 51 dries the ink attached to the sheet S being conveyed while conveying the sheet S toward the decurler 52. The decurler 52 corrects the curl of the sheet S. The decurler 52 conveys the decurled sheet S toward the second conveying portion 2.

As shown in FIG. 3, the printer 100 includes a control portion 6. The control portion 6 controls the print job performed in the printer 100. The printer control portion 6 controls the print job performed on the printer 100. In other words, the control portion 6 controls the operation of the first and second conveying portions 1 and 2, the belt conveying portion 3, the recording portion 4, the drying unit 51, and the decurler 52. In yet other words, the control portion 6 controls the conveyance of the sheet S and the ejection of ink by the recording heads 40. The control portion 6 also controls flushing processing by the recording heads 40.

To the control portion 6, a registration sensor 61, a sheet sensor 62, and a belt sensor 63 are connected. The sensing positions (arranged positions) of the registration sensor 61, the sheet sensor 62, and the belt sensor 63 are schematically shown in FIG. 4.

The sensing position of the registration sensor 61 is a position on the upstream side of the registration nip in the sheet conveying direction. The registration sensor 61 is, for example, an optical sensor of a reflective or transmissive type. The registration sensor 61 changes its output value according to whether or not the sheet S is present at the corresponding sensing position.

Based on the output value of the registration sensor 61, the control portion 6 senses arrival of the leading edge, and passage of the trailing edge, of the sheet S at the sensing position of the registration sensor 61. In other words, based on the output value of the registration sensor 61, the control portion 6 senses arrival of the leading edge, and passage of the trailing edge, of the sheet S at the registration nip. Based on the elapsed time since the arrival of the leading edge of the sheet S at the sensing position of the registration sensor 61, the control portion 6 adjusts the timing at which the pair of registration rollers 11 starts conveying the sheet S (the timing at which the pair of registration rollers 11 starts

rotating). Even if the sheet S is skewed, its conveyance by the pair of registration rollers 11 is started with the skew corrected.

The sensing position of the sheet sensor 62 is a position between the registration nip and the printing position of, of the plurality of line heads 41, the line head 41 at the most upstream side in the sheet conveying direction. The sheet sensor 62 changes its output value according to whether or not the sheet S is present at the corresponding sensing position. As the sheet sensor 62, a CIS (contact image sensor) or an optical sensor of a reflective or transmissive type may be used. For example, a CIS is used as the sheet sensor 62.

Based on the output value of the sheet sensor 62, the control portion 6 senses arrival of the leading edge, and passage of the trailing edge, of the sheet S at the sensing position of the sheet sensor 62. Based on the output value of the sheet sensor 62, the control portion 6 adjusts the timing at which to eject ink to the sheet S conveyed by the conveying belt 30. The control portion 6 may instead adjust the timing at which to eject ink to the sheet S conveyed by the conveying belt 30 based on the elapsed time since the start of the conveyance of the sheet S by the pair of registration rollers 11.

The control portion 6 measures the sheet passage time after the arrival of the leading edge of the sheet S at the sensing position of the sheet sensor 62 until the passage of the trailing edge of the sheet S at the sensing position of the sheet sensor 62. The sheet passage time at the sensing position of the sheet sensor 62 changes depending on the size of the sheet S in the conveying direction. Thus, the control portion 6, based on the sheet passage time, recognizes the size, in the conveying direction, of the sheet S conveyed by the conveying belt 30. In this way, even if the sheet S conveyed by the conveying belt 30 is of an irregular size, it is possible to make the control portion 6 recognize the size of the sheet S in the conveying direction.

Furthermore, the control portion 6 senses the deviation (skew) of the sheet S based on the output value of the sheet sensor 62 (read data obtained through reading by the sheet sensor 62). For example, after the conveyance of the sheet S by the pair of registration rollers 11 is started, the sheet S may deviate. In this case, the deviation of the sheet S is sensed by the control portion 6.

It is also possible to provide a plurality of sheet sensors 62. For example, two sheet sensors 62 may be provided.

The belt sensor 63 is a sensor for sensing a prescribed reference position (home position) of the conveying belt 30. The reference position of the conveying belt 30 is indicated by a predetermined mark. This allows the reference position of the conveying belt 30 to be sensed based on the output value of the belt sensor 63. For example, a CIS is used as the belt sensor 63. The belt sensor 63 may be configured using an optical sensor of a transmissive or reflective type.

The control portion 6 senses the reference position of the conveying belt 30 based on the output value of the belt sensor 63. In other words, the control portion 6 senses the position of a flushing area 31 (openings 310), which will be described later, in the circulation direction based on the output value of the belt sensor 63.

As shown in FIG. 3, the printer 100 includes a storage portion 7. The storage portion 7 includes storage devices such as a ROM, a RAM, an HDD, and an SSD. The storage portion 7 is connected to the control portion 6. The control portion 6 reads information from the storage portion 7. The control portion 6 writes information to the storage portion 7.

The printer 100 includes an operation panel 8. The operation panel 8 includes, for example, a touch screen. The touch screen displays software buttons, messages, etc., and accepts touch operations by a user. The operation panel 8 also includes hardware buttons for accepting settings, instructions, etc. The operation panel 8 is connected to the control portion 6. The control portion 6 controls display operation on the operation panel 8 (touch screen). The control portion 6 senses operations performed on the operation panel 8.

The printer 100 includes a communication portion 9. The communication portion 9 includes a communication circuit, etc. The communication portion 9 is connected to a user terminal PC via a network NT. The user terminal PC is an information processing apparatus such as a personal computer. The control portion 6 communicates with the user terminal PC using the communication portion 9. For example, print data (data including PDL data, etc.) for a print job transmitted to the printer 100 from the user terminal PC. In other words, a request to execute a print job is transmitted from the user terminal PC to the printer 100. Print data for a print job includes various types of setting data related to printing, such as the size of the sheet S to be used in the print job.

<Configuration of the Conveying Belt>

As shown in FIG. 5, the conveying belt 30 includes a flushing area 31. In FIG. 5, the flushing area 31 is enclosed by broken lines. The flushing area 31 is an area where openings 310 are formed that penetrate the conveying belt 30 in its thickness direction. In flushing processing, ink is ejected from the recording heads 40, and the ejected ink passes through the openings 310 to reach a receiving part 302 (see FIG. 4) arranged at the inner side of the conveying belt 30. The ink in the receiving part 302 is collected and discarded.

The conveying belt 30 has a plurality of flushing areas 31. The plurality of flushing areas 31 are arranged at predetermined intervals from each other in the circulation direction of the conveying belt 30.

Each flushing area 31 has a plurality of (the same number of) openings 310. The openings 310 are each an elongate hole extending in the width direction of the conveying belt 30. There is no particular limitation on the shape of the openings 310 (the shape as seen from the thickness direction of the conveying belt 30). It may be in a rectangular shape, circular shape, elliptical shape, or oval shape.

For example, each flushing area 31 includes two rows of openings. Each row of openings is a row of openings 310 that are arrayed at equal intervals in the width direction of the conveying belt 30. One row of openings has six openings 310, and the other row of openings has five openings 310. The middle of the rows of openings in the width direction coincides with the middle of the conveying belt 30 in the width direction. That is, the plurality of openings 310 in each flushing area 31 are arranged in a staggered formation in the width direction. Here, the length of the openings 310 in the width direction (i.e., opening width) is larger than the distance between two consecutive openings 310 in the width direction.

As shown in FIG. 6, a width W1 (mm) is smaller than a width W2 (mm). The width W1 corresponds to the length of the line head 41 in the width direction. Specifically, the width W1 corresponds to the length in the width direction from an end, at one side, of the recording head 40 located at the one side in the width direction to an end, at the other side, of the recording head 40 located at the other side in the width direction. The width W2 corresponds to the length of the

flushing area **31** in the width direction. Specifically, the width **W2** corresponds to the length in the width direction from an end, at one side, of the opening **310** located farthest to the one side in the width direction to an end, at the other side, of the opening **310** located farthest to the other side in the width direction.

Thus, as the conveying belt **30** is circulated, it is possible to make each of the plurality of nozzles **4N** in each recording head **40** face at least one of the openings **310** in the up-down direction. When, in flushing processing, ink that does not contribute to printing is ejected from each of the nozzles **4N**, it is possible to control such that the ink passes through the openings **310** (such that the ink does not attach to the conveying belt **30** and to the sheet **S**).

<Conveyance of the Sheet>

In printing on a plurality of sheets **S** of the same size conveyed sequentially by the conveying belt **30**, the control portion **6** controls such that the sheet-to-sheet distance, that is, the interval between the trailing edge of the foregoing sheet **S** and the leading edge of the subsequent sheet **S** (the sheet **S** conveyed after the foregoing sheet **S**) in the conveying direction (the dimension, in the conveying direction, of the region between the trailing edge of the foregoing sheet **S** and the leading edge of the subsequent sheet **S**) remains constant. That is, in this case, the control portion **6** controls such that a plurality of sheets **S** are conveyed at a constant interval (such that the sheet-to-sheet distance among the plurality of sheets **S** is constant). Successive printing on a plurality of sheets **S** of the same size conveyed sequentially at an interval by the conveying belt **30** corresponds to "successive printing", and will hereinafter be referred to simply as "successive printing".

Here, during successive printing, flushing processing is performed in the recording heads **40**. The control portion **6** controls the flushing processing by the recording heads **40**. The ink ejected in flushing processing does not contribute to printing. Thus, the control portion **6** controls such that the ink ejected in flushing processing passes through the openings **310**. That is, the control portion **6** makes the nozzles **4N** eject ink at a timing at which they face the openings **310** that do not overlap the sheet **S**.

To perform such control, the control portion **6** checks the size of the sheet **S** conveyed by the conveying belt **30**. The control portion **6** also senses the reference position of the conveying belt **30**. Then, the control portion **6** adjusts the tuning at which to start conveying the sheet **S** from the pair of registration rollers **11** to the conveying belt **30** so that the flushing areas **31** appear within the intervals of the sheets at a prescribed cycle. The control portion **6** changes the timing at which to start conveying the sheet **S** from the pair of registration rollers **11** to the conveying belt **30** according to the size of the sheet **S** conveyed by the conveying belt **30**. Before performing a print job, the control portion **6** checks the size of the sheet **S** to be used in the print job (the sheet **S** to be conveyed by the conveying belt **30**) based on print data for the print job to be performed.

The positional relationship between the sheets **S** conveyed by the conveying belt **30** and the flushing areas **31** is shown in FIG. 7. The circulation direction of the conveying belt **30** (the conveying direction of the sheet **S**) in FIG. 7 is the direction from right to left on the plane of FIG. 7. In FIG. 7, the flushing areas **31** are indicated by hatching, and the openings **310** are omitted. In FIG. 7, instead of the reference sign for the sheet **S**, the size of each sheet **S** is marked in the outline representing the sheet **S**. In FIG. 7, for the sake of convenience, a plurality of sheets **S** of different sizes are illustrated all together.

Now, with reference to FIG. 8, a detailed description will be given with focus on A4 portrait size. The circulation direction of the conveying belt **30** (the conveying direction of the sheet **S**) in FIG. 8 is the direction from bottom to top on the plane of FIG. 8. In FIG. 8, for the sake of convenience, three sheets **S** are shown, and they are identified by the suffixes **1** to **3** indicating the order of conveyance.

When the size of the sheet **S** is A4 portrait, no flushing area **31** appears between the first and second sheets **S1** and **S2**. A flushing area **31** appears between the second and third sheets **S2** and **S3**. The flushing area **31** between the sheets **S2** and **S3** does not overlap either the sheet **S2** or **S3** at all. Although not shown, no flushing area **31** appears between the third sheet **S3** and the fourth sheet **S**. and a flushing area **31** appears between the fourth and fifth sheets **S**.

<Flushing Processing>

Hereinafter, how the flushing processing by each recording head **40** is controlled will be described with focus on one recording head **40**. The other recording heads **40** are controlled similarly to the one recording head **40**. Thus, for the control of the other recording heads **40**, no overlapping description will be repeated.

The control portion **6** sets, as a control period for flushing processing in successive printing, the period after the arrival, at the printing position of the recording head **40** (the position opposite the recording head **40**), of the leading edge of the sheet **S** to be printed first (the first sheet **S**) in successive printing on a plurality of sheets **S** of the same size until the passage, at the printing position of the recording head **40** (the position opposite the recording head **40**), of the sheet **S** to be printed last (the last sheet **S**) in successive printing. During the set control period, the control portion **6** makes, of a plurality of nozzles **4N** in the recording head **40**, target nozzles **4Nt** (see FIG. 9) perform flushing processing.

Now, the target nozzles **4Nt** will be described in detail. The control portion **6** sets, out of the plurality of nozzles **4N**, the target of flushing processing. The nozzles **4N** set as such are the target nozzles **4Nt**. During the control period for flushing processing, the control portion **6** performs, as flushing processing, processing in which ink is ejected from the target nozzles **4Nt**.

When setting the target nozzles **4Nt**, the control portion **6** checks the size of the sheet **S** (the sheet **S** conveyed by the conveying belt **30**) used in successive printing. Then, based on the size of the sheets **S** in the width direction, the control portion **6** sets any of the plurality of nozzles **4N** as the target nozzles **4Nt**.

For example, suppose that the positional relations lie between the sheet **S** used in successive printing and the recording head **40** (a plurality of nozzles **4N**) as shown in FIG. 9. In this case, the control portion **6** sets, as the target nozzles **4Nt**, the nozzles **4N** located inside, in the width direction, a range **R1** that corresponds to the size, in the width direction, of the sheet **S** used in successive printing. In other words, the control portion **6** sets the nozzles **4N** that face the sheet **S** in the up-down direction during printing on the sheet **S** as the target nozzles **4Nt**. The target nozzles **4Nt** are the nozzles **4N** that contribute to printing on the sheet **S**. By contrast, the nozzles **4N** located outside the range **R1** in the width direction (the nozzles **4N** that do not face the sheet **S** in the up-down direction during printing on the sheet **S**) do not contribute to printing and are not set as the target nozzles **4Nt**.

When, during successive printing (during the control period for flushing processing), a flushing area **31** that does not overlap the sheet **S** at all faces the recording head **40**, the control portion **6** makes the recording head **40** eject ink, as

flushing processing, from the target nozzles 4Nt toward the openings 310. Hereinafter, a flushing area 31 that does not overlap the sheet S at all is referred to as a non-overlapping flushing area 31 and is distinguished from other flushing areas 31.

In an example shown in FIG. 8, suppose that the first sheet in successive printing is the sheet S1, then the time point at which the leading edge of the sheet S1 arrives at the printing position of the recording head 40 is the start point of the control period. In the example shown in FIG. 8, when the non-overlapping flushing area 31 between the sheets S2 and S3 faces the recording head 40, flushing processing is performed. Although not illustrated, a non-overlapping flushing area 31 appears also between the fourth and fifth sheets S, and, when the non-overlapping flushing area 31 faces the recording head 40, flushing processing is performed. From then on, non-overlapping flushing areas 31 appear between every two consecutive even- and odd-numbered sheets S, and, when a non-overlapping flushing areas 31 face the recording head 40, flushing processing is performed. That is, every time a non-overlapping flushing area 31 between sheets S conveyed by the conveying belt 30 reaches the position opposite the recording head 40, flushing processing is performed once.

When, during the control period for flushing processing, a flushing area 31 that partly overlaps the sheet S (a flushing area 31 that only in a part of it overlaps the sheet S) faces the recording head 40, the control portion 6 does not make the recording head 40 perform flushing processing. In the example shown in FIG. 8, when any of the flushing areas 31 that overlap the sheets S1, S2, and S3 respectively faces the recording head 40, no flushing processing is performed.

One example of control of flushing processing (including preparatory flushing processing, which will be described later) is shown in FIG. 10. As shown in FIG. 10, in a period Tn during which a non-overlapping flushing area 31 faces the recording head 40, the control portion 6 makes each of the target nozzles 4Nt eject in lines worth of ink (eject ink m times). The control portion 6, every time a non-overlapping flushing area 31 faces the recording head 40 (every time the period Tn comes), makes each of the target nozzles 4Nt eject n lines worth of ink as one session of flushing processing. For example, m equals 30.

Upon accepting a request for execution of a print job, the control portion 6 adds the accepted print job to a queue. When there are a plurality of printing jobs in the queue, the control portion 6 executes the plurality of printing jobs in the accepted order.

When the size of the sheet S to be used in a first print job of which the accepted order is Nth is the same as the size of the sheet S to be used in a second print job of which the accepted order is N+1, the control portion 6 executes the first and second jobs as a single job. In this case, the control portion 6 sets, as the control period for flushing processing, a period after the arrival of the first sheet S for the first print job at the printing position of the recording head 40 until the passage of the last sheet S for the second print job at the printing position of the recording head 40.

<Preparatory Flushing Processing>

Hereinafter, how preparatory flushing processing by the recording heads 40 is controlled will be described with focus on one recording head 40. The other recording heads 40 are controlled similarly to the one recording head 40. Thus, for the control of the other recording heads 40, no overlapping description will be repeated.

When the size of a first sheet S which is the sheet S conveyed first by the conveying belt 30 to be printed is

different from the size of a second sheet S which is the sheet S conveyed after the first sheet S to be printed, the control portion 6 performs switching processing to switch sheet supply sources. Thus, the sheet-to-sheet distance between the first and second sheets increases. As a result, the viscosity of the ink in the nozzles 4N increases before the second sheet S is printed, and this may cause nozzle clogging.

For example, the size of the sheet S used in the first print job which is Nth in the accepted order can be different from that used in a second print job which is (N-1)th in the accepted order. In this case, the control portion 6, after performing sheet feeding of the last sheet S for the first print job (first sheet S), performs switching processing, and then starts performing sheet feeding of the first sheet S for the second print job (second sheet S). Thus, the sheet-to-sheet distance between the first sheet S and the second sheet S increases.

When the size, in the width direction, of the second sheet S is larger than that of the first sheet S, in the printing on the second sheet S, the nozzles 4N that were not used in the printing on the first sheet S are used. In the nozzles 4N that have left unused long, the viscosity of ink tends to increase. Accordingly, it is preferable to perform, before printing on the second sheet S, processing for forcibly ejecting the ink in the nozzles 4N that were not used in the printing on the first sheet S (that is, flushing processing).

Thus, when, after printing on the sheet S of which the size in the width direction is the first size (hereinafter the first sheet S), printing on the sheet S of which the size in the width direction is the second size (hereinafter the second sheet S) that is larger than the first size is performed, the control portion 6, after the passage of the first sheet S at the printing position of the recording head 40 (the position opposite the recording head 40) before the arrival of the second sheet S at the printing position of the recording head 40, makes the recording head 40 perform, as preparatory flushing processing, processing in which ink is ejected toward the openings 310 from the nozzles 4N (corresponding to "first nozzles") that have not been set as the target nozzles 4Nt during printing on the first sheet S but will be newly set as the target nozzles 4Nt during printing on the second sheet S. Hereinafter, the nozzles 4N corresponding to the "first nozzles" are identified by the reference sign "401" and are referred to as the first nozzles 401.

The control portion 6 makes the recording head 40 further perform, as preparatory flushing processing, processing in which ink is ejected toward the openings 310 from the nozzles 4N (corresponding to "second nozzles") that have been set as the target nozzles 4Nt during printing on the first sheet S. Hereinafter, the nozzles 4N corresponding to the "second nozzles" are identified by the reference sign "402" and are referred to as the second nozzles 402.

For example, when a flushing area 31 that is on the downstream side of the second sheet S in the conveying direction and is closest to the second sheet S faces the recording head 40, the control portion 6 makes the recording head 40 perform preparatory flushing processing. Hereinafter, a flushing area 31 that is on the downstream side of the second sheet S in the conveying direction and is closest to the second sheet S is referred to as a preparatory flushing area 31 and is distinguished from other flushing areas 31. Here, a preparatory flushing area 31 is a flushing area 31 that does not overlap the sheet S at all.

In the example shown in FIG. 8, suppose that the second sheet S is the sheet S1. In this case, the flushing area 31 shown just above the sheet S1 is a preparatory flushing area

11

31. Although not illustrated, the flushing area 31 on the downstream side, in the sheet conveying direction, of the flushing area 31 shown just above the sheet S1 in FIG. 8 may be set as a preparatory flushing area 31.

Now, a more specific description of the first and second nozzles 401 and 402 will be given with reference to FIG. 11. In FIG. 11, the first and second sheets S are identified by the reference signs "Sa" and "Sb" respectively.

The first sheet Sa FIG. 11 is the sheet S of the first size and is the same size as the sheet S shown in FIG. 9. That is, during printing on the first sheet Sa, the nozzles 4N located inside, in the width direction, the range R1 that corresponds to the size of the first sheet Sa in the width direction are set as the target nozzles 4Nt (see FIG. 9). By contrast, during printing on the first sheet Sa, the nozzles 4N located outside the range R1 in the width direction are not set as the target nozzles 4Nt.

The second sheet Sb in FIG. 11 is the sheet S of the second size larger than the first size in the width direction. During printing on the second sheet Sb, the nozzles % IN located inside, in the width direction, a range R2 corresponding to the size of the second sheet Sb in the width direction are set as the target nozzles 4Nt. By contrast, during printing on the second sheet Sb, the nozzles 4N located outside the range R2 in the width direction are not set as the target nozzles 4Nt.

In the example shown in FIG. 11, after the first sheet Sa is fed, switching processing is performed. Thus, the sheet-to-sheet distance between the first and second sheets Sa and Sb increases. Here, in FIG. 11 for the sake of convenience, the reference sign "4Nt" is omitted.

In the example shown in FIG. 11, during printing on the first sheet Sa, the nozzles 4N located outside the range R1 in the width direction are not set as the target nozzles 4Nt. During printing on the second sheet Sb, the nozzles 4N located inside the range R2 in the width direction are set as the target nozzles 4Nt. Thus, in the example shown in FIG. 11, the nozzles 4N located outside the range R1 in the width direction but inside the range R2 in the width direction are the first nozzles 401. The nozzles 4N located inside the range R1 in the width direction are the second nozzles 402.

When a preparatory flushing area 31 faces the recording head 40, the control portion 6 makes the recording head 40 perform, as preparatory flushing processing, processing in which a first amount of ink is ejected from each of the first nozzles 401. Furthermore, the control portion 6 makes the recording head 40 perform, as preparatory flushing processing, processing in which a second amount of ink smaller than the first amount is ejected from each of the second nozzles 402.

The first amount is larger than the second amount. That is, the amount of ink ejected by each of the first nozzles 401 in preparatory flushing processing is larger than the amount of ink ejected by each of the second nozzles 402 in preparatory flushing processing. The amount of ink ejected by each of the second nozzles 402 in preparatory flushing processing is equal to or larger than the amount of ink ejected by each of the target nozzles 4Nt in ordinary flushing processing.

For example, as shown in FIG. 10, in a period T0 during which a preparatory flushing area 31 faces the recording head 40, the control portion 6 makes each of the first nozzles 401 eject n_2 lines worth of ink (eject ink n_2 times), where n_2 is larger than the number of ink ejection lines in ordinary flushing processing with the target nozzles 4Nt. For example, n_2 equals 100.

In the period T0 during which a preparatory flushing area 31 faces the recording head 40, the control portion 6 makes each of the second nozzles 402 eject n_3 lines worth of ink

12

(eject ink n_3 times), where n_3 is equal to or larger than the number of ink ejection lines in ordinary flushing processing with the target nozzles 4Nt. For example, n_3 equals 50.

In this embodiment, as described above, when printing is performed on the second sheet Sb (the sheet S of the second size larger than the first size in the width direction) after printing on the first sheet Sa (the sheet S of the first size), the control portion 6, after the passage of the first sheet Sa at the printing position of the recording head 40 (the position opposite the recording head 40) before the arrival of the second sheet Sb at the printing position of the recording head 40, makes the recording head 40 perform, as preparatory flushing processing, processing in which ink is ejected toward the openings 310 from the first nozzles 401 that have not been set as the target nozzles 4Nt during printing on the first sheet Sa but will be newly set as the target nozzles 4Nt during printing on the second sheet Sb.

Here, the first nozzles 401 are the nozzles 4N that do not contribute to printing during successive printing. Thus, even when the nozzles 4N that correspond to the first nozzles 401 are not set as the target nozzles 4Nt (even though flushing processing with the nozzles 4N is not performed), it has no effect on image quality. In this way, by controlling such that flushing processing with the nozzles 4N that do not contribute to printing is not performed, it is possible to reduce the amount of ink consumed in flushing processing.

On the other hand, the first nozzles 401 are the nozzles 4N that contribute to printing during subsequent printing. Thus, if the viscosity of the ink in the nozzles 4N corresponding to the first nozzles 401 is high, it affects image quality in subsequent printing. Accordingly, before subsequent printing, preparatory flushing processing for forcibly ejecting the ink in the first nozzles 401 is performed. Thus, even when no flushing processing is performed with the first nozzles 401 during successive printing, it is possible to suppress clogging of the first nozzles 401 in subsequent printing. That is, it is possible to suppress degradation of image quality in subsequent printing.

In this way, in this embodiment, it is possible to reduce the amount of ink consumed in flushing processing while suppressing degradation in image quality.

In conventional flushing processing, for example, the same amount of ink is ejected from each of the nozzles. That is, from the nozzles that do not contribute to printing, the same amount of ink as that from the nozzles that contribute to printing is ejected in flushing processing. Conventional control has a disadvantage of an increased amount of ink consumed in flushing processing increases.

In this embodiment, as described above, the control portion 6 makes the recording head 40 further perform, as preparatory flushing processing, processing in which ink is ejected toward the openings 310 from the second nozzles 402 that have been set as the target nozzles 4Nt during printing on the first sheet Sa. With this configuration, it is possible to suppress clogging of the second nozzles 402. As a result, it is possible to suppress degradation in image quality in subsequent printing.

In this embodiment, as described above, the amount of ink ejected by each of the first nozzles 401 in preparatory flushing processing is larger than the amount of ink ejected by each of the second nozzles 402 in preparatory flushing processing. Here, since the first nozzles 401 are not used in successive printing, they are more likely to be clogged than the second nozzles 402 used in successive printing. However, the amount of ink ejected by the first nozzles 401 in preparatory flushing processing is larger than that ejected by

13

the second nozzles 402. Thus, it is possible to reliably suppress clogging of the first nozzles 401.

In this embodiment, as described above, the amount of ink ejected by each of the second nozzles 402 in preparatory flushing processing is equal to or larger than the amount of ink ejected by each of the target nozzles 4Nt in ordinary flushing processing. That is, the amount of ink ejected by each of the first nozzles 401 in preparatory flushing processing is larger than the amount of ink ejected by each of the target nozzles 4Nt in ordinary flushing processing. This helps suppress clogging of the first nozzles 401 more reliably.

Here, when printing on the second sheet Sb (the sheet S of the second size) is performed after successive printing on a plurality of first sheets Sa (the sheets S of the first size) sequentially conveyed by the conveying belt 30, the larger the number of first sheets Sa used in successive printing (the number of printed sheets in successive printing), the longer the first nozzles 401 are left unused. Here, by performing capping processing in which the nozzle face of the recording head 40 is covered by a cap, dehydration in the nozzle face (the ink in the nozzles 4N) of the recording head 40 is suppressed. However, during printing, capping processing of the recording heads 40 is not performed. Thus, the longer the time spent for successive printing, the longer the first nozzles 401 are left unused, and this increases the viscosity of the ink in the first nozzles 401 (the first nozzles 401 are dehydrated more easily).

Thus, in this embodiment, when printing on the second sheet Sb is performed after successive printing on a plurality of first sheets Sa sequentially conveyed by the conveying belt 30, the control portion 6 recognizes the number of printed sheets in successive printing, and, the larger the recognized number of printed sheets, the larger the control portion 6 makes the amount of ink ejected by each of the first nozzles 401 in preparatory flushing processing. In this way, even when, in printing after successive printing on a large number of printed sheets, a sheet S that is larger, in the width direction, than the sheet S used in successive printing is used, it is possible to suppress degradation of image quality.

The embodiments disclosed herein should be understood to be in every aspect illustrative and not restrictive. The scope of the present disclosure is not limited by the description of the embodiments given above but by the appended claims, and encompasses any modifications made within a sense and scope equivalent to those of the claims.

What is claimed is:

1. An ink-jet recording apparatus comprising:
a conveying belt that is supported so as to be able to move around, the conveying belt conveying a recording medium by circulating;
a recording head that is arranged opposite the recording medium, the recording head having a plurality of nozzles that are arrayed in a width direction perpendicular to a circulation direction of the conveying belt, the recording head printing on the recording medium by ejecting ink from the nozzles; and
a control portion that controls flushing processing by the recording head,
wherein

14

the conveying belt has a plurality of flushing areas with openings formed therein,

the flushing areas are arranged at predetermined intervals from each other in the circulation direction,

the control portion

sets the nozzles that face the recording medium during printing on the recording medium as target nozzles, and

when the flushing area that does not overlap the recording medium faces the recording head, makes the recording head eject ink, as the flushing processing, from the target nozzles toward the openings, and

when, after printing on the recording medium of which a size in the width direction is a first size, printing is performed on the recording medium of a second size that is larger, in the width direction, than the first size, the control portion, after passage of the recording medium of the first size at a position opposite the recording head before arrival of the recording medium of the second size at the position opposite the recording head, makes the recording head perform preparatory flushing processing in which ink is ejected toward the openings from first nozzles that have not been set as the target nozzles during printing on the recording medium of the first size but will be newly set as the target nozzles during printing on the recording medium of the second size, and

when printing on the recording medium of the second size is performed after successive printing on a plurality of recording media of the first size sequentially conveyed by the conveying belt, the control portion recognizes a number of printed sheets in the successive printing, and, the larger the number of printed sheets, the larger the control portion makes an amount of ink ejected by each of the first nozzles in the preparatory flushing processing.

2. The ink-jet recording apparatus according to claim 1, wherein

the control portion makes the recording head further perform, as the preparatory flushing processing, processing in which ink is ejected toward the openings from second nozzles that have been set as the target nozzles during printing on the recording medium of the first size.

3. The ink-jet recording apparatus according to claim 2, wherein

an amount of ink ejected by each of the first nozzles in the preparatory flushing processing is larger than the amount of ink ejected by each of the second nozzles in the preparatory flushing processing.

4. The ink-jet recording apparatus according to claim 2, wherein

the amount of ink ejected by each of the second nozzles in the preparatory flushing processing is equal to or larger than the amount of ink ejected by each of the target nozzles in the flushing processing.
